UNITED STATES PATENT OFFICE

HARRY F. VICKERS, OF LOS ANGELES, CALIFORNIA

HIGH SPEED PUMP

Application filed February 25, 1932. Serial No. 342,603.

This invention has to do with a reciprocating pump and it is a general object of the invention to provide a high speed reciprocating pump.

- Reciprocating pumps, in general, depend upon the suction action of the pistons operating outwardly in the cylinders to draw the fluid into the pump preliminary to its being forced from the pump under pressure. In practice such pumps operate satisfactorily at low or moderate speeds, however, they do not operate efficiently or in a practical way at high speeds, as the fluid does not act in a manner to follow the pistons, with the result that partial vacuum or voids are drawn in the cylinders. This results in improper or inefficient charging of the cylinders and hammering or knocking, which is disagreeable and destructive.
- It is a general object of the present invention to provide a reciprocating pump mechanism embodying means whereby fluid properly follows the piston action, even though the piston speed may be very high.
- It is another object of the present invention to provide an improved, efficient reciprocating pump of the rotary type capable of operation at high speeds.

It is a further object of the invention to provide a pump operable at high pressures without appreciable leakage or loss through the valve means.

The various objects and features of the present invention will be best and more fully understood from the following detailed description of a typical form and application of the invention, throughout which description reference is had to the accompanying drawings, in which:

- Fig. 1 is an end view of the mechanism embodying the invention showing the parts at one side of the center line broken away to show in section, the section being through the cylinders and plungers of the mechanism. Fig. 2 is a longitudinal side view of

the mechanism showing the parts above the center line in vertical central section. Fig. 3 is a detailed transverse sectional view through the fluid feed being a view taken as indicated by line 3-3 on Fig. 2, and Fig. 4 is a detailed plan section, being a view taken as indicated by line 4-4 on Fig. 1.

The present invention has to do, generally, with the reciprocating type of pump and is concerned primarily with the provision of such a pump capable of efficient, full capacity operation at high speeds. The invention is particularly suited for embodiment in or application to the rotary type of reciprocating pump, such type of pump being well adapted for high speed operation. I will therefore describe the invention as applied to a rotary type of reciprocating pump in which the cylinder block and plungers operating in the cylinders of the block revolve as a unit within a casing, the reciprocation of the plungers in the cylinders being caused by cooperation between slippers on the outer ends of the plungers and an eccentric in the casing. It is to be understood, however, that the broader principles of the invention are not to be considered limited to the specific details herein set forth as they may be applied to other constructions.

The mechanism embodying the present invention includes, generally, a cylindrical casing A, a cylinder block B rotatably mounted in the casing on a shaft C, plungers D slidably carried in the cylinders of the block B, slippers E on the plungers, an eccentric F in the casing forming a bearing on which the slippers E operate, valve means G controlling flow of fluid to and from the cylinders of the block, and feeding means H operable to supply fluid to the valve means so that it will follow the action of the plungers even at high speeds of operation.

The casing A includes an annular body 10, ends 11 and 12 closing the ends of the body, mounting brackets 13 on the parts just men-

tioned, and various other features of construction as will be apparent from the drawings. In the construction shown the end 11 is integral with the body while the end 12 is separable from the body, being attached thereto by means of cap screws 14. The shaft C, which carries the cylinder block, extends into the casing through the end 11 and continues through the end 12 and means H, as will be hereinafter described. The shaft C is supported in the ends 11 and 12 by means of bearings 15. The end of the shaft projecting from the end 11 of the casing can be engaged for the purpose of driving the shaft.

The cylinder block B is fixed, for instance, keyed on the shaft C within the body 10 and between the ends 11 and 12. The block is provided with a plurality of radially disposed cylinder openings 16 and has a hub extension 17 extending into a central hub-like extension 18 of the end 12. The plungers D are slidably carried in the cylinders 16.

The shoes or slippers E are pivotally connected to the outer ends of the plungers and slidably operate in the internal eccentric bearing 19 of the eccentric F. The bearing 19 is circular or annular and is offset or eccentric to the axis of the cylinder block B so that the plungers are caused to reciprocate in the cylinders as the slippers follow the bearing 19. This general action is that commonly found in mechanisms of this general type. During operation centrifugal force holds the plungers and slippers out, maintaining the slippers in bearing engagement with the eccentric. The eccentric is normally stationary in the casing and therefore may be considered a part or portion of the casing.

The valve means G is provided to control the flow of fluid between an inlet port 20 and the several cylinders 16. The port 20 is located in the extension 18 of the end 12, and the valve means G is located in the hub extension 17 of the cylinder block B. There is an annular recess 21 in the valve means G to continuously register with the port 20. Inlet valves 22 connect the recess 21 with cylinder ports 23, there being one port 23 extending to each cylinder. Outlet valves 24 connect the cylinder ports 23 with an outlet port 25 formed in the shaft C. The valves 22 and 24 are preferably reciprocating valves, say, spring pressed ball valves.

Through this valve arrangement fluid is drawn into the cylinders from the port 20 through the recess 21, valves 22, and ports 23 during outward movement of the plungers in the cylinders, and is forced from the cylinders through the ports 23 and valves 24 and into the port 25 during inward movement of the plungers in the cylinders. The shaft C extends through the end 12 and through the feeding means H and the port 25

extends to the end of the shaft where it may be connected with an outlet conduit 30 through a suitable packing connection 31.

The feeding means H is arranged at the outer end of the central extension 18 of the end 12 and operates to receive fluid through a port 32 and deliver it to the port 20 under pressure.

The means comprises a fluid handling mechanism carried in a housing 33 secured to the extension 18. In the particular form of the invention shown I have illustrated a conventional form of gear pump for handling the fluid. This mechanism includes a gear 35 fixed on the shaft C within the housing 33 meshing with a gear 36 carried in the housing 33.

The housing fits closely around the gears 35 and 36 so that fluid admitted to the port 32 which communicates with one side of the meshing parts of the gears is carried around by the gears and delivered to a port 37 at the opposite side of said point.

The port 37 is formed through or in the housing 33 and communicates with the port 20 so that the fluid handled by the gear pump is delivered to the port 20 or is supplied to the valve means G under pressure.

It will be apparent that as the speed of rotation of the mechanism varies, the capacity of the gear pump varies, so that fluid is always supplied to the valve means G under pressure.

Further, it is to be understood that other forms of fluid handling means, other than a gear pump may be used in the means H. For instance, I may use a mechanism of the type set forth in my co-pending application entitled Vane pump or motor, filed Feb. 25, 1929, Serial Number 342,602.

In operation fluid admitted to the port 32 is handled by the means H, that is, by the pump mechanism embodied in the means H, so that it is positively fed or delivered to the valve means G. This causes the fluid to be fed into the cylinders 16 positively so that the filling of the cylinders as the pistons move outwardly is not dependent solely upon the suction action, it being obvious, however, that the full benefit of the suction action is utilized together with the positive feed action. As above described, the fluid entering the cylinders as the plungers move outwardly is forced from the cylinders and out through the valves 24 and port 25 as the plungers move inwardly. The pressure exerted on the fluid by the inward movement of the plungers is greater than that with which the fluid is fed to the port 20, so that the inlet valves 22 are properly closed.

Having described only a typical, preferred form of my invention, I do not wish to limit myself to the specific details set forth, but wish to reserve to myself any changes or variations that may appear to those skilled in the art or fall within the scope of the following claim:

Having described my invention, I claim:

In a pump, a casing, a shaft extending into the casing, a block on the shaft within the casing and having a plurality of radial cylinders, an eccentric ring surrounding the block, pistons in the cylinders operable through engagement with the ring, valve means in the block and shaft for controlling the admission and discharge of fluid to and from the inner ends of the cylinders, a housing at an end of the casing surrounding the shaft, and a pump in the housing operable by the shaft to supply fluid under pressure to the valve means through a port in the casing.

In witness that I claim the foregoing I have hereunto subscribed my name this 25th day of January, 1929.

HARRY F. VICKERS.
